(57) **CLAIM**

The ornamental design for a drivetrain for vehicle, as shown and described.

DESCRIPTION

The application file contains at least one drawing executed in color. Copies of this patent application publication with color drawing(s) will be provided by the Office upon request and payment of the necessary fee.

FIG. 1 illustrates a front side view of the drivetrain for vehicle, showing our new design;

FIG. 2 illustrates a rear side view of the drivetrain for vehicle of FIG. 1;

FIG. 3 illustrates a top side view of the drivetrain for vehicle of FIG. 1;

FIG. 4 illustrates a bottom side view of the drivetrain for vehicle of FIG. 1;

FIG. 5 illustrates a right side view of the drivetrain for vehicle of FIG. 1;

FIG. 6 illustrates a left side view of the drivetrain for vehicle of FIG. 1;

FIG. 7 illustrates a left isometric view of the drivetrain for vehicle of FIG. 1; and

FIG. 8 illustrates a right isometric view of the drivetrain for vehicle of FIG. 1.

FIG. 9 illustrates a black and white front side view of the drivetrain for vehicle of FIG. 1;

FIG. 10 illustrates a black and white rear side view of the drivetrain for vehicle of FIG. 1;

FIG. 11 illustrates a black and white top side view of the drivetrain for vehicle of FIG. 1;

FIG. 12 illustrates a black and white bottom side view of the drivetrain for vehicle of FIG. 1;

FIG. 13 illustrates a black and white right side view of the drivetrain for vehicle of FIG. 1;

FIG. 14 illustrates a black and white left side view of the drivetrain for vehicle of FIG. 1;

FIG. 15 illustrates a black and white left isometric view of the drivetrain for vehicle of FIG. 1; and,

FIG. 16 illustrates a black and white right isometric view of the drivetrain for vehicle of FIG. 1.
